US00D956987S

(12) **United States Design Patent** (10) Patent No.: **US D956,987 S**
(45) Date of Patent: ** Jul. 5, 2022

(54) **ELECTRICAL STIMULATION DEVICE**

(71) Applicant: **CHECKPOINT SURGICAL, INC.**,
Cleveland, OH (US)

(72) Inventors: **Derek Lewis**, Cleveland, OH (US);
Steve Galecki, Cleveland, OH (US);
Trevor Kucherak, Cleveland, OH
(US); **Eric Walker**, Berea, OH (US)

(73) Assignee: **CHECKPOINT SURGICAL, INC.**,
Cleveland, OH (US)

(**) Term: **15 Years**

(21) Appl. No.: **29/768,282**

(22) Filed: **Jan. 28, 2021**

(51) LOC (13) Cl. **28-03**

(52) U.S. Cl.

USPC **D24/200**; D24/144

(57) **CLAIM**

The ornamental design for an electrical stimulation device,
as shown and described.

DESCRIPTION

FIG. 1 is a perspective view of an electrical stimulation device showing our new design;

FIG. 2 is a first side view thereof;

FIG. 3 is a second side view thereof;

FIG. 4 is a rear view thereof;

FIG. 5 is a front view thereof;

FIG. 6 is a top view thereof; and,

FIG. 7 is a bottom view thereof.

The broken lines in the figures are included for the purpose
of illustrating portions of an electrical stimulation device
and form no part of the claimed design.

1 Claim, 7 Drawing Sheets
